UNITED STATES PATENT OFFICE.

MATHEW B. MORGAN, OF CLEVELAND HEIGHTS, OHIO, ASSIGNOR TO THE CLEVELAND TRACTOR COMPANY, OF EUCLID, OHIO, A CORPORATION OF OHIO.

TRACK-BELT.

1,357,718.

Specification of Letters Patent. Patented Nov. 2, 1920.

Application filed May 31, 1919. Serial No. 300,866.

To all whom it may concern:

Be it known that I, MATHEW B. MORGAN, a citizen of the United States, residing at Cleveland Heights, in the county of Cuyahoga and State of Ohio, have invented a certain new and useful Improvement in Track-Belts, of which the following is a full, clear, and exact description.

This invention relates to endless track belts adapted for use as parts of track laying tractors. The object of the invention is to produce a serviceable track belt at a minimum cost. The invention consists in a track belt consisting of units or links constructed, and connected together substantially as shown in the drawings and hereininafter described as pointed out definitely in the appended claims.

In the drawing, Figure 1 is a plan view of two connected links of a track belt which embodies the invention; Fig. 2 is a side elevation of the same two track links; Fig. 3 is a front elevation of one of said links; Fig. 4 is a transverse vertical section in the plane of line 4-4 on Fig. 2; Fig. 5 is a plan view of the blank from which the top member of each link is formed; Fig. 6 is a side elevation of a link which embodies the invention but is slightly different in some respects from that shown in the preceding figures; Fig. 7 is a front elevation of the link shown in Fig. 6.

Each of the links consists of two members formed by cutting and bending sheet metal plates. These two members are a top member 10, and a foot 20.

Each top member, when completed, comprises as integral parts two parallel side members 12 a transversely cylindrical front member 14, and a transversely extended cylindrical rear member 15.

To produce this top member, a flat and substantially rectangular metal plate is employed. (See Fig. 5.) The middle part of this plate between the two side members 12 is punched out, forming a central rectangular opening, but some of the metal so punched out is left in the form of two tongues which remain attached respectively to the front and rear ends of the plate. The front tongue and the front end of the plate to which this tongue is attached are then bent, both upward and downward out of the plane of the plate, and into approximately cylindrical form to form the small front cylinder 14. This cylinder is not complete, but it might be, and as shown is complete enough for all practical purposes. The rear tongue and the rear end of the plate to which the tongue is attached are then bent to form the large cylinder 15. This cylinder is not complete, as shown, but it is complete enough for all practical purposes. The metal of which it is formed is bent both below and above the plane in which the side members 12 lie; and, in bending the metal to form this large cylinder, said metal is bent around the front cylinder of an adjacent link thereby hinging the links together. The small cylinder serves as the hinge pintle, and the large cylinder as the sleeve in which said pintle is rotatably fitted.

The foot member 20 includes a bottom plate or shoe 21, having two turned up sides 22. The width of the shoe of this foot member is preferably greater than the width of the top member, and therefore these sides extend upwardly at an inclination toward each other, while at their upper ends the distance between is substantially equal to the width of the top member. The extreme edges of these upturned sides are bent into horizontal position, thereby forming horizontal flanges 23 which go beneath and are secured preferably by welding to the sides of the top of the top member.

The front end of the shoe or bottom plate of the front member is bent downwardly to form a ground engaging transverse grouser 25. This is preferably in the form of a loop, the extreme end 26 of which passes beneath and is welded or otherwise secured to the lower face of the shoe 21.

When a belt is made of members constructed as shown and described, and when these links are connected together in sufficient number to form an endless chain, this chain is admirably adapted for use as a track belt upon a track laying tractor.

The side members 12 of the successive links lie in the same plane, and there is only a small gap between their adjacent ends. These side members therefore serve as the rails for the weight-supporting rollers or wheels of the tractor to ride on. The central opening in this plate permits the teeth of the sprocket wheels of the tractor to engage the external surface of the rear cylinder 15.

It will be understood that it is not necessary that the downturned front end of the shoe of each link shall be in loop form, as shown in Fig. 2. It may be simply a downturned flange as shown in Fig. 6, and this downturned flange may or may not be reinforced, as shown in Fig. 6. It will also be understood that it is not essential that the edges of the upturned side members of the front pass beneath the sides of the top members, as shown in Fig. 4, although this is the preferable construction of these side members. They may have their upper edges engaging with the edge of the upper member, and these engaging edges may be beveled and welded together substantially as shown in Figs. 6 and 7.

Having described my invention, I claim:

1. A track belt for track laying tractors comprising a plurality of pivotally connected links, each of which is composed of a foot member and an open rectangular frame-like top member which overlies and is connected with said foot member, each top member comprising two flat parallel sides, a transverse cylinder intermediate of the sides and at one end of the member, and another transverse cylinder of different diameter intermediate of the sides at the other end of the member, each of the smaller cylinders being embraced by and rotatable within the larger cylinder of the next adjacent link.

2. A track belt for track laying tractors comprising a plurality of pivotally connected links, each of which comprises an open rectangular top member having two parallel flat side bars and cylindrical cross bars of different diameters extending between the side bars at the front and rear ends of said top member, and a foot member having upturned sides which engage with and are secured to the side bars of the top members, the small cylindrical cross bar of each link being embraced by and rotatable within the large cylindrical cross bar of the next adjacent link. 35

3. A track belt for track laying tractors, comprising a plurality of pivotally connected links, each of which comprises an open rectangular top member having two parallel flat side bars and cylindrical cross bars of different diameters extending between the side bars at the front and rear ends of said top member, and a foot member having upturned sides which along their upper edges are bent into horizontal position and are extended beneath and are secured to the side bars of the top member, the small cylindrical cross bar of each link being embraced by and rotatable within the large cylindrical cross bar of the next adjacent link. 50

In testimony whereof, I hereunto affix my signature.

MATHEW B. MORGAN.
